UNITED STATES PATENT OFFICE.

WELLINGTON H. KIDDER, OF ROOSEVELT, NEW YORK, ASSIGNOR, BY MESNE ASSIGNMENTS, TO UNDERWOOD COMPUTING MACHINE COMPANY, OF NEW YORK, N. Y., A CORPORATION OF NEW YORK.

MAGAZINE FOR LOOSE LEAVES.

1,291,923.

Specification of Letters Patent.

Patented Jan. 21, 1919.

Application filed December 26, 1914. Serial No. 879,015.

To all whom it may concern:

Be it known that I, WELLINGTON H. KIDDER, a citizen of the United States, residing in Roosevelt, Long Island, in the county of 5 Nassau and State of New York, have invented certain new and useful Improvements in Magazines for Loose Leaves, of which the following is a specification.

This invention relates to means to facilitate the handling of a quantity of loose leaves, which may be supported in a pile on a stand or work-table, when it is desired, for example, to make entries on different sheets or leaves without permitting them to 10 become disarranged, or to get out of a certain order.

The invention is particularly adapted for use in connection with a work-supporting table or leaf used as an adjunct to a stand 20 or support for a typewriting machine, particularly one which is combined with a computing mechanism. A pile of loose sheets may be placed on the work-table when it is desired to make typewritten entries on certain selected sheets or on all the sheets 25 *seriatim*, which are removed one at a time from the pile to receive the entries, each sheet after the entries have been made thereon being restored to the work-table prior to the 30 removal of the succeeding sheet.

The present invention provides means for holding the sheets in their proper order and position on the work-table, preventing them from being misplaced when returned to the 35 work-table and facilitating the selection and removal of individual sheets.

In carrying out the invention, there may be mounted on the work-table, impaling pins projecting upwardly above the surface of 40 the table, to engage marginal perforations in the work-sheets. These impaling pins may be curved and arranged with their upper ends adapted to be brought together, so that each pair forms a ring or loop.

45 Suitable mechanism is provided beneath the top surface of the work-table, for opening and closing the rings. The work-table may be formed with a longitudinal recess or trough, to accommodate said mechanism. 50 The latter may comprise a pivot rod extending longitudinally of the trough, on which rod the impaling pins are mounted, said pins having arms within said trough and operatively connected as by means of 55 cam slots and pins, with a rock shaft also

extending longitudinally within said trough. By rocking the shaft in one direction, the rings are opened, permitting the work-sheets to be placed thereon or removed.

The pile of work-sheets may be placed on 60 the pins, so as to extend at one side of the pins. The sheets may then be individually removed to have typewritten entries made thereon, each sheet being placed on the opposite pins after the entries have been made. 65 Said rock shaft may be actuated to close the said rings, so that the sheets may be turned over as the leaves of a book from one side to the other without becoming disengaged from the pins, thereby enabling any selected 70 sheet to be brought to the top of the pile for removal.

An operating handle may be positioned adjacent the typewriter stand and operatively connected to the said rock shaft, the 75 handle thus being in convenient position for manipulation by an operator seated at the stand.

Other features and advantages will hereinafter appear.

In the accompanying drawings,

Figure 1 is a front elevation view of a supporting stand for a typewriting machine or a computing machine, with the invention applied to a work-table or leaf of the stand. 85

Fig. 2 is a plan view of the work-table with the loose-leaf holder mounted thereon.

Fig. 3 is a part sectional front elevation view on a larger scale, showing the loose-leaf holder in closed position.

Fig. 4 is a similar view, showing the said holder in open position.

Fig. 5 is a sectional elevation view taken longitudinally of the leaf-holding mechanism.

Fig. 6 is a detail perspective view, showing a holding ring in closed position.

A stand on which a writing machine, adding machine, or combined writing and computing machine 1 may be mounted, comprises up-rights or legs 2, a top 3 and cross braces 4. Work-tables 5 and 6 at opposite sides of the stand are shown as hinged leaves removably attached to the stand by means of brackets 7 formed with open ends 100 or hooks to engage rods 8, said leaves being supported at their outer edges by diagonal brace rods 9, the lower ends of which enter sockets 10 on the frame of the stand.

The means for holding the loose leaves or 110

workpieces in position on the work-table comprises pairs of holding pins 11 forming rings or loops which may be arranged in a row extending forwardly and rearwardly 5 across the work-table 5. These holding pins are supported and actuated by mechanism located beneath the surface of the table, allowing the work-sheets or leaves 12 to lie flat on the table.

- 10 The table 5 has a portion cut away to form a longitudinal trough or compartment 13 to receive a pivot rod 14 on which the pins 11 are mounted, and a rock shaft 15, also beneath the table, has suitable means 15 for swinging the pairs of pins 11 to opened and closed positions. The connections between the shaft 15 and the holding pins 11 comprise pins or rods 16, which in effect are cams, fixed to the shaft 15 and extending 20 through cam slots 17 in arms 18, which arms may form integral extensions of the pins 11.

When the shaft 15 is in the Fig. 3 position the rods 16 hold the impaling pins 11 in closed position with their outer ends abutting to form a closed loop or ring on which the leaves 12 may be guided and turned over like the leaves of a book, to project in either direction from the ring. The leaves 12 may be provided with perforations to receive the 30 pins 11. These may be the usual perforations commonly provided in ledger leaves and the like for use with loose leaf binders. By rotating the shaft 15 from the Fig. 3 position to the Fig. 4 position, the pins 16 are carried along the cam slots 17, and thereby swing the arms 18 apart, separating the impaling pins 11 as shown in Fig. 4.

The rock shaft 15 has portions cut away 40 opposite each pair of impaling pins to accommodate the arms 18. In other words, the shaft 15 comprises cylindrical sections united by integral webs 19 opposite the arms 18. As shown in Fig. 4, these webs 19 may form positive means to hold the 45 impaling pins in open position, the surfaces of the webs playing the part of cams. The shaft 15 may be rocked by means of an operating handle 20 on a lever fulcrumed at 21 and connected through a link 22 to an arm 50 23 fixed to the forward end of the rock shaft 15. The movement of the handle 20 is limited by stops 24. The handle 20 is located within convenient reach of the operator.

55 The compartment 13 may be provided with lateral recesses or slots 25 to accommodate the portions of the pins 11 beneath the surface of the table 5. The opening 13 in the table is covered by a plate 26, 60 which may be set into the table so that its upper face is flush with the surface of the table, and said plate is formed with slots 27 through which the pins 11 project.

65 In use, a pile of work-sheets 12, such as loose leaf ledger sheets, bills, or other work-

pieces, may be placed on the open pins as in Fig. 4; the handle 20 may then be swung to the Fig. 3 position closing the pins 11, so that any number of the leaves 12 may be turned over on the pins from one side to 70 the other to bring to the top of the pile a selected leaf.

For example, a series of leaves 12 may be placed in a pile on the right-hand pins 11, the sheets facing upward. The top sheet 75 may then be removed and placed on the machine 1, and typewritten entries made thereon. After such entries have been made, the sheet may be placed on the left-hand pins, face downward. Each succeeding 80 sheet in the right-hand pile may in turn be removed to receive entries and then return to the left-hand pins, so that the order of the sheets is retained. If it is desired to select individual leaves from different 85 parts of the pile, or series, the operator closes the holding rings by swinging the handle 20 to the right, allowing any number of leaves to be thrown over on the rings to bring to the top of the pile the selected 90 sheet. The handle 20 may then be thrown to the left, opening the rings and permitting the removal of the selected sheet. In all these operations, the order of the sheets is retained without any special thought or effort 95 on the part of the operator. The leaves are also supported and kept in a perfectly flat condition.

Variations may be resorted to within the scope of the invention, and portions of the 100 improvements may be used without others.

Having thus described my invention, I claim:

1. The combination with a work-table, said table formed with a recess or compartment below the surface of the table, of impaling pins arranged in pairs along said recess and projecting upwardly above the surface of the table to enter perforations along the edges of work-sheets arranged in 105 a pile or piles on the surface of the table, a pivot rod within said opening on which said pins are pivotally mounted, said pins having arms extending below said pivot rod, a rock shaft within said recess, and connecting means between said rock shaft and said arms for actuating the impaling pins when said rock shaft is rocked, so that in one position of the rock shaft the pins of each pair are brought together and form a 110 loop on which the work-sheets may be guided and turned from one side to the other, said pins being separated by a movement of the rock shaft to another position to permit the removal of the work-sheets. 115

2. The combination with a work-table formed with a recess or compartment therein extending in a forward and rearward direction, of impaling pins for loose work-sheets or leaves, said pins extending up- 120 125 130

- wardly above the surface of the table and arranged in pairs along said compartment, means within said compartment for pivotally mounting said pins, said pins having 5 arms extending beneath the pivotal mounting, an actuating rod extending longitudinally within said compartment and bearing against said arms, to swing the pins about their pivots into and out of position to form 10 closed loops on which the work-sheets may be guided and turned from one side to the other of the impaling pins, and means at the front of the table for actuating said rod.
3. The combination with a work-table 15 formed with a recess or compartment therein extending in a forward and rearward direction, of impaling pins for loose work-sheets or leaves, said pins extending upwardly above the surface of the table and 20 arranged in pairs along said compartment, means within said compartment for pivotally mounting said pins, said pins having arms within said compartment, an actuating rod extending longitudinally within said 25 compartment and having operative connection with said arms, to swing the pins about their pivots into and out of position to form closed loops on which the work-sheets may be guided and turned from one side to the 30 other of the impaling pins, means at the front of the table for actuating said rod, said actuating means comprising a handle located at a point remote from said rod, and connections between said handle and said 35 rod for actuating the latter.
4. The combination with a work-table having a substantially flat top surface and formed with a recess or compartment therein extending in a forward and rearward direction, of impaling pins for loose work-sheets or leaves, said pins extending upwardly above the surface of the table and 40 arranged in pairs along said compartment, means within said compartment for pivotally mounting said pins, said pins having arms extending beneath the pivotal mounting, an actuating rod extending longitudinally within said compartment and having operative connection with said arms, to 45 swing the pins about their pivots into and out of position to form closed loops on which the work-sheets may be guided and turned from one side to the other of the impaling pins, means at the front of the table 50 for actuating said rod, and a cover plate for said compartment provided with slots through which said pins extend, said plate being flush with the sheet-supporting surface of the table to permit such sheets to lie 55 flat upon the table, while mounted on said pins.
5. The combination with a work-table, of pins mounted beneath the table and project- 60
- ing above the table so that perforated work-sheets may be impaled on said pins and lie 65 on either side thereof, said pins adapted to be swung in a vertical plane so that they co-operate in pairs to form smooth guides, and an operating handle having means effective on said pins beneath the table, for positively 70 moving the pins to and from each other, so as to separate the pairs of pins to enable the work-sheets to be impaled on either set of pins.
6. The combination with a work-table, of pins mounted beneath the table and projecting above the table so that perforated work-sheets may be impaled on said pins and lie 75 on either side thereof, said pins adapted to be swung in a vertical plane so that they co-operate to form smooth guides, extensions of said pins below the surface of the table, and a revoluble shaft beneath the table comprising cams adapted to engage said extensions for positively moving the pins to and 80 from each other, so as to separate the pairs of pins to enable the work-sheets to be impaled on either set of pins.
7. The combination with a table, of semi-circular pins pivoted beneath said table so 85 that work-sheets impaled on said pins may lie on the table on either side thereof, a pivot-rod on which said pins are mounted in pairs beneath the surface of said table, extensions of said pins beyond said rod, and a 90 shaft revoluble to positively open and close the pairs of pins by moving said extensions.
8. The combination with a table, of semi-circular pins pivoted beneath said table so 95 that work-sheets impaled on said pins may lie on the table on either side thereof, a pivot-rod on which said pins are mounted in pairs beneath the surface of said table, extensions of said pins beyond said rod, a 100 shaft lying between said extensions, comprising cams adapted to be turned to force the extensions apart to separate the pins to permit work-sheets to be impaled thereon, and other camming devices on said shaft for 105 positively closing the extensions together to 110 cause the pairs of pins to form circles on which the impaled sheets may be turned.
9. The combination with semi-circular impaling pins and a pivot-rod on which they are mounted, of extensions beyond said rod 115 and lying outside the circle formed by the closed pins, a shaft lying between said extensions, camming surfaces on said shaft adapted to cam said extensions apart, and pins on said shaft adapted to enter slots in 120 said extensions for positively drawing the extensions together.

WELLINGTON H. KIDDER.
